(57) **CLAIM**

I claim the ornamental design for a electronic component, as shown and described.

DESCRIPTION

FIG. 1 is a top, front perspective view of an electronic component;

FIG. 2 is a bottom, rear perspective view of the electronic component;

FIG. 3 is a front view thereof;

FIG. 4 is a top elevated view thereof;

FIG. 5 is a left elevated view thereof;

FIG. 6 is a right elevated view thereof;

FIG. 7 is a rear elevated view thereof;

FIG. 8 is a bottom view thereof; and,

FIG. 9 is a magnified section of an opening located along the 45 degree orientation proximate the right side of the electronic component.
